UNITED STATES PATENT OFFICE.

EMANUEL CINER, OF NEW YORK, N. Y.

DESIGN FOR A RING.

Application filed October 25, 1928. Serial No. 28,635. Term of patent $3\frac{1}{2}$ years.

To all whom it may concern:

Be it known that I, EMANUEL CINER, a citizen of the United States, and residing at New York, in the county of New York and State of New York, have invented a new, original, and ornamental Design for Rings, of which the following is a specification, reference being had to the accompanying drawing, forming part thereof.

The figure is a plan view of a ring, showing my new design.

I claim:

The ornamental design for a ring, as shown.

EMANUEL CINER.
